DESIGN FOR A DEODORANT CONTAINER

Arthur J. Kangas, Detroit, Mich.

Application November 10, 1947, Serial No. 142,438

Term of patent 7 years

(CL. D16—2)

To all whom it may concern:

Be it known that I, Arthur J. Kangas, a citizen of the United States, residing at Detroit, in the county of Wayne and State of Michigan, have invented a new, original, and ornamental Design for a Deodorant Container, of which the following is a specification, reference being had to the accompanying drawing, forming part thereof.

In the drawings:

I claim:

The ornamental design for a deodorant container, as shown.

ARTHUR J. KANGAS.
